UNITED STATES PATENT OFFICE

2,439,230

INTERMITTENT CURRENT OPERATED
MOTOR

Carl S. Weyandt, Homer City, and Edward J. Misien, Indiana, Pa., assignors to Sytron Company, Homer City, Pa., a corporation of Delaware

Application March 5, 1946, Serial No. 652,074

6 Claims. (Cl. 172—126)

1

This invention relates generally to reciprocating electric motors operated by interrupted current impulses and more particularly to the mechanical structure and the method of constructing the same.

This invention is a continuation-in-part of application that issued on July 2, 1946 as Patent No. 2,403,034.

The principal object of the present invention is the provision of an electromagnetic core for a reciprocating electric motor and the method of constructing the same.

Another object is the provision of an improved case for a reciprocating electric motor.

Another object is the provision of an improved coil for the electric motor and the method of winding the same.

Other objects and advantages appear in the following description and claims.

A practical application illustrating the principles of this invention is shown in the accompanying drawings wherein:

Fig. 1 is a view in section of the electric hammer.

Fig. 2 is a view in side elevation of the electric hammer with parts shown in section.

Fig. 3 is a view in transverse section of the electromagnetic core taken along the line 3—3 of Fig. 5.

Fig. 4 is a view in longitudinal section of the electromagnetic core.

Fig. 5 is a view in elevation of a partially assembled electromagnetic core.

Referring particularly to Figs. 3, 4 and 5, the electromagnetic core 10 is constructed on the tubular barrel 11 made of nonmagnetic material such as brass, bronze, or a suitable alloy such as aluminum. The bore of the barrel 11 is cylindrical as shown at 12 and its perimetral surface is made up of a series of flat surfaces 13, the number of which depend upon the number of circumferential groups of laminae employed in the core. The perimetral surface of the barrel illustrated is octagonal in shape to receive eight laminae in each of the three circumferential groups 14, 15 and 16, and the groups 14 and 16 are the same. Each of the laminae groups 14 and 16 have axially disposed portions 17 and radial portions 18. The lamina group 15 has an axial portion 20 and the radial portions 21 respectively. The end laminae groups 14 and 16 are provided with the inwardly projecting pole faces 23 and 24 respectively, whereas each laminae of the intermediate group 15 is provided with the pole faces 25 and 26, one at each end 55

2

thereof. The pole of each group projects through windows 22 in the wall of the barrel and the pole faces are preferably flush with the bore. Each of the pole faces is preferably hardened since they are exposed to the reciprocating armature 27 made of magnetizable material and having welded or otherwise attached to its end the members 28 of nonmagnetic impact resisting material, such as Stellite or its equivalent.

The barrel 11 is provided with the outwardly projecting flanges 29 and 30 at the ends thereof, the perimetral surfaces of which are arranged to receive the rings 31 and 32 which magnetically connect the laminae of the groups 14 and 16.

In assembling the core 10, the rings 31 and 32 are pressed in place on the perimetral surface of the flanges and the laminae groups are then placed in position and temporarily tied by the wire loops or bands 33 which securely hold them in assembled relation. The end laminae groups 14 and 16 are then welded or brazed as at 34 to secure them to the rings 31 and 32 respectively. The other or inner ends of the laminae groups 14 and 16 are then brazed to the perimetral surface of the barrel as shown at 35 and 36. Each of the intermediate laminae group 15 is also brazed at either end to the barrel as shown at 37 and 38. Thus the eight laminae sections of each group 14, 15 and 16 are permanently secured to the barrel 11 and their poles 23 to 26 are exposed in the bore of the barrel. The temporarily tied wires or bands 33 may then be removed.

The gaps between the ends of the laminae in adjacent groups are then closed by the two nonmagnetic bridge members 40 and 41 by welding their ends as indicated at 42. By using two bridge members between each laminae section the core member is materially opened up permitting greater air circulation and also decreasing the weight of the core over that shown in Patent 1,797,253 without sacrificing efficiency. Improved electrical characteristics are also obtained by the use of this core structure.

After the bridge members have been secured 45 to the core member 10 they form an octagonal surface. It is then chucked in a lathe and the perimetral longitudinal portions of the laminae and bridge members are turned to provide a substantially cylindrical surface 43 as indicated on 50 the left side in Fig. 3, and the pole faces 23, 24, 25 and 26 are ground flush with the bore 12. This fabricated core member 10 thus provides two grooves or spool sections for receiving electromagnetic coils.

A series of annular grooves 44 are cut in the

perimetral surface of the bridge members 40 and 41 and in the axial sections 17 and 20 of the three groups of laminae as shown in Fig. 5.

Split insulating washers 45 are then assembled on the core member adjacent the radial sections 18 on both sides of the central radial section 20 as shown in Fig. 1. The intermediate surface of the laminae groups and the bridge members are then varnished and wound with one layer of insulating cord 46. The insulating cord is wound so that it fills the grooves 44 and provides a smooth and uniform spool surface. A fine cotton string is then wound over the core to fill it up and the whole of the insulating surface is varnished. Two layers of linen tape half lapped are then wound on the string and cord and independently varnished to form the insulation 46. Since the insulating cord and string are tightly wound and interlock in the grooves 44 they provide a very firm and uniform foundation for the insulating tape and the coils. This foundation is substantially cylindrical. The electromagnetic coils 48 and 52 are then uniformly wound tightly on the core, with the first layer imbedding itself into the insulation on the core, and are covered with insulation. The lead wires of the coils are taken out at one end of the core as indicated at 51. Thus the motor windings are firmly locked on the core and when subjected to vibration will not become loose or become otherwise inoperative due to continued vibration of the hammer, since the cord 46 is embedded and interlocked in the grooves 44 and the wire is embedded in the insulation and the cord. This structure provides a material improvement in this hammer.

The electromagnetic core 10 is then inserted into the cylindrical casing 50. A nose casting 53 is fitted on the lower end of the casing and is provided with a recess to receive the lower end of the tube 11 and the ring 31. As shown in Fig. 2 the nose casting 53 is provided with oppositely disposed ears 54 having holes therethrough to receive the assembly bolts 55 which extend upwardly on each side of the casing 50 and pass through aligned holes in the top or handle casting 56.

The nose casting 53 is provided with a series of radially disposed ribs 57. A series of holes 58 are cut in the nose casting 53 to permit the air to pass from the coils and through the holes 59 from the bore of the barrel.

The bushing 60 is held in the bore of the nose casting by the spring 61 which is secured by the lock washers and bolts 62.

The ends of the casing 50 are beveled to lock into the matched surfaces of the nose and handle castings which are held in assembled relation by the nuts 63 on the bolts 55 as shown in Fig. 2. The spring 64 held by the bolts 65 has a central recess fitting around the barrel 66 and engages the outer end of the core stop clamping the core ring 67, the inner end of which engages the core stop seat 68. The radial flange of the seat 68 engages the core member 10 and the cylindrical portion fits into the bore of the core member. Thus the core member 10 is held by the nose casting 53, the nose bushing 60 and spring 61 at one end and by the seat 68 and spring 64 at the other end. A double spring 70 is held on the bolts 55 by the nuts 71 and is provided with a central aperture that fits over the top of the barrel 66. The double spring engages the annular flange 72 on the outer surface of the barrel forcing it down against the top of the flange of

the seat 68. The top of the barrel 66 is closed by the plug seat 73 which is engaged by the upper end of the coil spring 74. The lower end of the spring holds the core stop 75 against the seat 68 and the lower end of the stop projects in the bore of the electromagnetic core 10 in which the reciprocable core member 27 operates. The core stop barrel 66 and the core stop 75 are vented to prevent entrapment or compression of air therein due to the fast reciprocating action of the movable core member 27.

The top or handle casting 56 has the rotary motor casing 76 formed integral therewith for housing the field 77 and the armature 78. The upper end of the armature shaft is supported in the frictionless bearing 79 which permits limited axial movement of the armature. The other end of the casing 76 is provided with an enlarged bore to receive the flanges casting 80 having a central sleeve supported by the radial arms 81 and has an axial bore to receive the lower frictionless bearing 82. The outer race of the bearing 82 is slideable axially within the bore of the casting 80 and is supported by the helical spring 83 resting on the cap 84. The inner race of the bearing 81 seats against the shoulder 85 on the armature shaft. A perforated disc 86 is mounted in the bottom end of the casting 80.

The armature shaft has the fan member 87 secured thereto. As the motor rotates air is drawn into the vortex of the fan through the perforated screen 88 and past the radial arms 81. The fan member 87 then forces the air radially through the passageway 89 into the annular chamber 89 in the lower end of the handle casting 57 from whence it flows axially of the hammer passing between the casing 52 and the coils 48 and 50 and down between the laminae sections inside the coils to the lower end of the casing 40 where it is discharged through the openings 58 in the nose casting 53 to cool the hammer coils. This circulation of air permits the use of less iron and coils of lower resistance.

As disclosed in the parent case the series 45 wound motor is connected in multiple with the lower hammer coil 48 on the line side of the trigger switch 90 mounted in the hollow handle of the handle casting 56. The hammer is operated on half wave alternating current which may be supplied by rectifiers. One half of the alternating current wave is valved to operate one hammer coil and the other half the other hammer coil. Although the operation of the hammer and the series motor are controlled by the switch 90, the rectifiers are controlled by an alternating current switch adjacent thereto and are ordinarily energized during a job but the hammer is stopped and started when needed. When the hammer is not used for relatively long periods of time the rectifiers are deenergized.

We claim:

1. An electromagnetic reciprocating motor field comprising a tubular barrel of nonmagnetic material, a plurality of spaced circumferential 65 groups of radially disposed laminated core members secured to the barrel, the core members of the groups being aligned and having pole faces exposed to the interior of the barrel, a pair of parallel bridge members connecting the adjacent ends of the core members to provide a continuous support therebetween to form a coil base on the core members, a series of annularly disposed grooves formed in the perimetral surface on the core members, insulation material wound 70 around the core members and in the grooves, and

a wire coil wound on the insulating material and interlocking with the insulation in the grooves to firmly lock the coil against movement relative to the core members.

2. An electromagnetic reciprocating motor field comprising a tubular barrel of nonmagnetic material, a plurality of spaced circumferential groups of radially disposed laminated core members secured to the barrel, the core members of the groups being aligned and having pole faces exposed to the interior of the barrel, a pair of parallel bridge members secured to and connecting the adjacent ends of the aligned core members to provide a continuous support therebetween to form a coil base on the core members, the perimetral surface of the core and bridge members being arcuate, a series of grooves formed in the perimetral arcuate surface of the core and bridge members, insulating material wound around the core and bridge members and in the grooves, and a wire coil wound on the insulating material and interlocking with the insulation in the grooves to firmly lock the coil against movement relative thereto.

3. An electromagnetic reciprocating motor field comprising a tubular barrel of nonmagnetic material, a plurality of spaced circumferential groups of radially disposed laminated core members secured to the barrel, each core member having an outwardly extending portion and a longitudinally extending portion with a pole face exposed to the interior of the barrel and the core members of the groups being aligned, a pair of parallel bridge members secured to and connecting the adjacent ends of the aligned longitudinal portions of the core members to provide a continuous support forming a coil base between the outwardly extending portions, the perimetral surfaces of the longitudinal portions and the bridge members being arcuate and having a series of grooves formed therein, insulating material wound around the said continuous support and in said grooves, and a wire coil wound on the insulating material and interlocking with the insulation in the grooves to firmly lock the coil against movement relative thereto.

4. A casting for a reciprocating motor consisting of a bell-shaped end chamber arranged to receive and seal with a tubular housing containing the reciprocating motor, a rotary motor

chamber formed integral with one side of the bell-shaped end chamber and having a fan chamber interposed between the rotary motor chamber and the bell-shaped chamber, and said casting providing a straight passage connecting the fan chamber with the bell-shaped end chamber to direct air thereto for cooling the reciprocating motor.

5. A handle casting for a reciprocating motor consisting of a hand grip having a bell-shaped end chamber arranged to receive and seal with a reciprocating motor housing, a rotary motor chamber formed integral with one side of the hand grip and with its axis parallel to that of the bell-shaped chamber, a fan chamber integral with the rotary motor housing and the handle, and said casting providing a lateral discharge from the fan chamber to the bell-shaped chamber for the discharge of cooling air to the motor housing.

10 6. In a reciprocating motor the combination of a tubular housing enclosing a reciprocating motor, a nose casting enclosing the working end of the motor housing, a handle casting enclosing the other end of the motor housing, means to 15 secure said housing and castings in assembled relation, a bell-shaped chamber in the handle casting opening into the motor housing, a cooling motor housing formed integral with the handle housing and having a rotary motor mounted 20 therein, a fan driven by the rotary motor to cool the same, a housing for the fan formed integral with the handle housing and providing a straight discharge to the bell-shaped chamber for directing 25 a portion of the air to cool the reciprocating 30 motor.
